UNITED STATES PATENT OFFICE.

JOHN LOUIS REYNOLDS, OF LONG ISLAND CITY, NEW YORK, ASSIGNOR, BY MESNE ASSIGNMENTS, TO ELECTRICAL RESEARCH PRODUCTS INC., A CORPORATION OF DELAWARE.

SWITCHING APPARATUS AND SYSTEM.

Application filed April 1, 1927. Serial No. 180,826.

This invention relates to switching systems, and with particularity to the automatic connection of sound transmitters with a sound reproducer.

5 The invention is in the nature of an improvement upon the switching arrangement disclosed in my copending application Serial No. 180,823, filed April 1, 1927. In application Serial No. 180,823, there is disclosed a synchronized sound and picture projecting system wherein an electrical network or "fader" is employed to effect the connection in succession of a plurality of electromechanical reproducers with a common sound projecting device. It has been found in the operation of such systems that, due to carelessness, the attendant operator may, at times, allow the "fader" to remain connected with the sound reproducer while 10 the motor for driving the associated electro-mechanical translator is changing speed. This results in a gradual change of pitch in the sound projected from the reproducer and may seriously mar the pleasing quality 15 of the program.

It is one of the principal objects of the invention therefore to automatically "cut out" a transmitter when the speed of an associated driving motor begins to vary.

20 A feature of the invention is in the combination of motor-driven sound translating devices associated with each other and with a common sound reproducer through an electrical network, together with a switch automatically operated to effectively "cut out" a translating device when the associated motor is not running at the required speed.

In synchronized sound and picture systems where the sound record is embodied in 25 a separate medium from that of the picture film, for example, in a wax record, it is essential that the sound record driving motor be driven at a fixed and uniform speed. This is particularly important when successive sound records are to be reproduced, in order that no change in pitch may occur from one record to another. However, at 30 times it may be desirable to operate the picture projector alone, and at a different speed from that fixed for a synchronized program.

Accordingly, it is a feature of the invention to provide a switch and circuit arrangement for controlling the speed of the motor which drives a picture projector and sound

reproducer, whereby, with the switch in one 55 position, the speed of the driving motor is fixed at the proper value, while in another position of the switch the operator is enabled to vary the speed of the driving apparatus.

Other features and advantages inherent 60 in the invention will be revealed by a consideration of the descriptions given herein-after and as specifically pointed out in the appended claims.

For this purpose the invention is shown 65 and described in its relation to a sound translating and reproducing system, but it is understood that the inventive idea is capable of application to other types of sound transmission systems, as will be apparent to those 70 familiar with the art to which the invention relates. Furthermore, only such parts of a sound reproducing system are illustrated in the drawing as are considered necessary to obtain a complete understanding of the invention and one preferred mode of employing 75 it.

Fig. 1 shows schematically a control system embodying my invention while Fig. 2 is a characteristic curve of the system. 80

Referring to the drawing, there is shown in the upper left portion thereof a picture projecting machine of known construction P¹, and a phonograph turntable 25 carrying a disc sound record 16, both the projector and the turntable being driven through suitable gearing from the motor M₁ which has an auxiliary field winding 1. Motor M₁ may be of any suitable type whose speed can be controlled by the strength of the current 85 through the auxiliary field winding. In the drawing, an alternating current motor is shown, the armature of which receives current from the alternating current source 3 when switch S₁ is operated either to the right 90 or to the left. Motor M₁ drives a small generator G₁ which delivers alternating current to the input circuit of the three-element vacuum tube T₁ whose output circuit includes a marginal relay 4, and the field winding 1. While a separate battery 28 is shown for supplying the plate potential for tube 95 T₁, it is obvious that extra windings may be placed on generator G₁ for supplying both the plate potential and filament currents. 100

The input circuit of the tube T₁ comprises the inductance L₁ and either the variable condenser 5 or the fixed condenser 6, depend- 105

ing upon whether switch S_1 is in its left or right-hand position. Included in the input circuit of tube T_1 is the grid polarizing battery 7 which is normally adjusted so that 5 when motor M_1 is operating at the required speed for a synchronized picture and sound program, the current in the output circuit is sufficient to operate relay 4. It is to be noted that for such a program, switch S_1 is operated to its right-hand position with the fixed 10 condenser 6 connected in the input circuit of the tube T_1 . Condenser 6 and inductance L_1 are of such values that the current flowing in the plate circuit of the tube is sufficient to 15 operate relay 4, this current remaining constant so long as motor M_1 is rotating at the proper speed required for a synchronized program. Fig. 2 illustrates the manner in which the current through auxiliary field 1 20 varies with the frequency of the currents from generator G_1 , and consequently in accordance with changes in the motor speed. The curve of Fig. 2 corresponds to the resonance curve of the tuned circuit including 25 the condenser 5, or condenser 6, and the inductance L_1 . The values of inductance and capacity 6 are preferably so chosen that when the motor M_1 is rotating at the proper speed required for a synchronized sound and 30 moving picture program, the current in the output circuit of tube T_1 and the field winding 1 has the value P . Should, therefore, for any reason, motor M_1 slow down, the 35 frequency of the currents applied to the input circuit of tube T_1 will be lowered, resulting in an increase of current through the field 1, and a corresponding increase of the motor speed. Should motor M_1 tend to increase its speed, the field current becomes 40 less and the motor steadies down to the required speed. When it is desired to use the picture projector P_1 independently of the sound reproducing apparatus, it may be convenient to operate the said projector at a 45 different speed from that set by the inductance L_1 and condenser 6. For this purpose the switch S_1 is operated to its left-hand position, causing the fixed condenser 6 to be replaced by the variable condenser 5, the 50 operator is now enabled to vary the speed of motor M_1 simply by adjusting the condenser 5, which varies the working point on the resonance curve and the strength of the field current. 55 Assuming that a synchronized sound and moving picture program is to be reproduced and that the first part of the program is carried by the record 16, and a succeeding part by the record 17, the attendant operates 60 switch S_1 to its right-hand position, completing a circuit for the lamp 8 which remains lighted as a continuous signal, which may be seen from a distance, that the apparatus is operating at the speed required for 65 a synchronized program. Plugs 19 and 20

having been previously inserted in jacks 21 and 23, the artificial line AL is connected at one end to the phonograph reproducing equipment R_1 , and at the other end to the reproducing apparatus R_2 . It is to be noted that the apparatus shown in the lower left-hand portion of Fig. 1 is similar to that shown in the upper right-hand portion and further description thereof at this point is believed to be unnecessary. 75

It is desirable that the sound projecting apparatus represented schematically by the loud speaker 12 be disconnected while the motor M_1 is changing speed. This change of speed may be unavoidable as, for example, 80 during the very short interval that the motor requires to come up to full speed, or because of failure of the power supply to operate the motor within the required speed limits. For this purpose relays 4 and 22 are provided. 85 As hereinbefore described, relay 4 is marginal and only receives sufficient current to be operated, when the motor M_1 is rotating at the speed required for a synchronized program. While the motor is coming up to 90 speed, the current in the plate circuit of tube T_1 is insufficient to operate relay 4, and a circuit is completed from ground through the winding of relay 22, sleeve of jack 21, 95 sleeve of plug 19, contacts of relay 4, contacts 33 and 34 of switch S_1 , to battery and ground. Relay 22 is operated over this circuit and maintains a short-circuit around the electromechanical translator 15 while the motor M_1 is changing speed, thus preventing 100 any gradual changes of pitch in the loudspeaker 12, which would occur if device 15 were not short-circuited.

When the turntable 25 has attained the proper speed, as fixed by condenser 6 and inductance L_1 , marginal relay 4 operates and relay 22 releases to remove the short circuit from the device 15 which is actuated by the stylus 14 following the sound groove in the disc 16. Device 15, therefore, generates 105 sound modulated currents corresponding to the varying amplitudes of the groove and feeds these currents into the artificial line AL . The operator then adjusts the contacts 110 35 and 36 to include a greater or less number of sections of the line AL in circuit with the translator 15 and the input circuit of the electron discharge amplifier A whose output circuit is connected to the loudspeaker 12. The points at which the contacts 23, 24 are 115 to be set to give the proper volume of sound in the loudspeaker 12 may be determined in advance of the starting of motor M_1 , in which case the setting of these contacts may be accomplished while the motor is attaining 120 speed or at any previous time.

When the end of the reel in the picture projector P_1 , and the end of the cutting-in disc 16, are about to be reached, the attendant opens switch S_1 and operates switch 125

S_2 to the right. Motor M_1 then starts to slow down and motor M_2 comes up to speed. While motor M_1 is slowing down, the current in the output circuit of tube T_1 is diminishing, relay 4 releases and relay 22 operates, thus preventing the device 15 from affecting the loudspeaker 12. Similarly, while motor M_2 is changing speed, relay 26 is normal and relay 24 operates to close the circuit of relay 22 which maintains a short circuit around the device 27. While the switchover from motor M_1 to motor M_2 is being effected the attendant moves contacts 35 and 36 downwardly to a predetermined point beyond the electrical midsection of the line AL , thus decreasing the number of sections of the line AL in circuit with device 27 and the amplifier A and allowing the reproducer R_2 to take control of the loudspeaker 12.

If it is desired to blend the sound-modulated currents from translator 15 into those from the translator 27, the attendant allows the motor M_1 to remain running when the end of the record in disc 16 is about to be reached and starts the motor M_2 . Consequently relay 4 remains operated and device 15 continues to feed currents into the line AL until the actual end of the record is reached. Just prior to the end of the record in disc 16 being reached, the attendant moves contacts 35 and 36 downwardly to a predetermined point beyond the center of the line AL . The line AL may be so proportioned that with the contacts 35, 36 in the center of the line, the effect of either device 15 or 27 upon the loudspeaker 12 is substantially zero. As the contacts 35, 36 move beyond the midpoint of the line AL , the currents from device 27 increase in strength and reproducer R_2 takes control. Contacts 35, 36 may form part of a rotary switch such as disclosed in my copending application Serial No. 180,323, filed April 1, 1927 in which event the movement of these contacts may be made almost instantaneously and without the switchover from device 15 to device 27 being noticeable to an auditor. For a detailed description of the manner in which the artificial line AL functions to control the switchover and blending effects, reference may be had to my copending application Serial No. 180,323, hereinbefore referred to.

Should it be desired to operate the picture projecting machine and sound reproducing apparatus synchronously at a different speed from that set by condenser 6, switches S_1 and S_2 are operated to the left and the variable condensers adjusted to the point corresponding to the desired speed. Under these circumstances switches 31 and 32 are opened that relays 4 and 26 may be ineffective to cause short-circuiting of the line AL as hereinabove described.

It is obvious that the invention, while

shown in connection with a reproducing system employing wax records may also be used in systems employing photographic records, in which case, if the sound record is on the same film as the motion picture, 70 the turntable 25 is not required. In this case the reproducer 15 is replaced by a photoelectric cell which is excited in accordance with the varying transparencies of the photographic sound record. It is also desirable in 75 such a reproducing system to couple the output of the photoelectric cell to the line AL by means of vacuum tubes, in order to render the variations in the photoelectric current most effective. It is also clear that the 80 sound record may be on a distinct film from the motion picture, in which case the turntable 25 is replaced by a picture projector for the sound record. Absolute synchronism 85 between the photographic sound record and the motion picture is assured because of the mechanical connection between the respective driving shafts.

While in the foregoing description and in the drawing specific apparatus is disclosed, 90 it is understood that the invention is not to be limited thereto. For example, the driving motors M_1 , M_2 may be direct current motors instead of the alternating current type, and devices 15, 27 may take the form 95 of any other known apparatus for electromagnetically translating sound variations into corresponding electric currents. It is also within the scope of the invention to use a single motor for driving both turntables 100 and both picture projectors, in which case the respective turntables and projectors would be connected through suitable clutch apparatus to the driving motor.

What is claimed is:

1. In combination, a sound translating device comprising a driven element, a motor for driving said element, a sound reproducing device operated under control of said translating device, and means automatically controlled by said motor for rendering said translating device ineffective to control said reproducer while the speed of said motor is varying.

2. In combination, a sound translating mechanism comprising a rotatable element and an electrical "pick-up" device, a sound reproducer associated with said device, a motor for driving said element, switching means responding to changes in speed of said motor, said switching means effective to electrically disassociate said "pick-up" device from said reproducer when said motor is changing speed.

3. In combination, a driving motor, a relay responsive only when said motor is running at a definite speed, a device for translating a sound record into current impulses, said device having a member driven from said motor, a sound reproducer to be oper-

ated by said current impulses, and means controlled by said relay for short-circuiting said translating device.

4. In combination, a plurality of devices for generating sound modulated currents, each device comprising a rotatable member, means for driving each of said rotatable members, a network with which said devices are associated, a reproducer also associated with said network, means for progressively varying the point of association of said reproducer with said network to effectively switch said reproducer from one to the other of said devices, and automatically operated means for short-circuiting said other device when the associated driving means is varying in speed.

5. In combination, a plurality of devices for generating sound modulated currents, a network to which said currents may be applied simultaneously, a reproducing device associated with said network, means for adjusting the point of association of said reproducer with said network to effectively switch the control of said reproducer from one to the other of said devices, and a relay for cutting off electrically said other device from the reproducer until said other device is generating the sound modulated currents at the proper general pitch.

6. In combination, a plurality of mechanical media sound records, means for driving each of said records, a device associated with each record for producing correspondingly modulated currents, a sound reproducer, means for switching said reproducer from one to the other of said devices without interruption, and automatic means for short-circuiting said other device until the associated driving means has reached a required speed.

7. In combination, a plurality of devices for translating mechanical variations into voice modulated current impulses, each device comprising a driven member, means for mechanically driving each of said members, an electrical sound reproducer to be operated under control of said impulses, switching means for transferring the control of said reproducer from one to the other of said devices, said control being electrically ineffective as long as the driving means associated with said other device is operating below a predetermined speed.

8. In combination, a plurality of devices for translating a record of sound variations into corresponding current variations, each device comprising a driven element, a motor for driving said element, a non-adjustable tuned circuit for controlling the speed of

said motor, an adjustable tuned circuit for varying the speed of said motor, a reproducer operated by said impulses, a switch for associating either of said circuits with said motor, means effective when said non-tuned circuit is associated with said motor for cutting out said reproducer when said motor varies in speed, and means for rendering said last mentioned means ineffective when said tuned circuit is associated with said motor.

9. In combination a sound translating device, driving means for said device, a second reproducing device operated under control of said translating device, means for regulating the speed of said driving means comprising an electron discharge device having its input controlled by said driving means, the output of said discharge device in turn controlling the speed of said driving means, and means controlled by the output of said discharge device to render said transmitting device ineffective to control said reproducer while the speed of driving means is varying.

10. In combination a sound translating mechanism comprising a driven element, an electrical pickup device, means for driving said element, means for controlling the speed of said driving means, an electron discharge device having its input circuit controlled by said driving means, the output of said discharge device in turn controlling said speed controlling means, a non-adjustable tuned circuit associable with the input of said discharge device, an adjustable tuned circuit associable with the input of said discharge device, a switch adapted in one position to associate said non-adjustable circuit with said device and in another position to associate said adjustable circuit with said device, and visual indicating means adapted to be permanently operable so long as said non-adjustable circuit is associated with said device.

11. In combination an electromagnetic sound reproducer, a motion picture projecting mechanism, means effective when a synchronized sound and picture program is to be reproduced for driving said reproducer and said picture mechanism at predetermined speed ratios, means for rendering said sound reproducer ineffective when said ratio is departed from, means for changing said ratio without rendering said sound reproducer ineffective, and a visual signal permanently lighted so long as said predetermined ratio is not departed from.

In testimony whereof, I have signed my name to this specification, this 18th day of March 1927.

J. LOUIS REYNOLDS.
